UNITED STATES PATENT OFFICE

GEORGE L. JONES, OF GARDEN CITY, NEW YORK, ASSIGNOR TO SPERRY PRODUCTS, INC.,
OF BROOKLYN, NEW YORK, A CORPORATION OF NEW YORK

RAIL FLAW DETECTOR

Application filed January 28, 1931. Serial No. 511,659.

This invention relates to rail flaw detectors, and particularly to the carriage which carries the brushes and the detector coils, as shown and described in the patent of Elmer A. Sperry, No. 1,820,505, granted August 25, 1931, for Fissure detector for metals. Said carriage having a flanged guide wheel at each end adapted to engage the rail, is mounted, one at each side of the car, in such manner that it is free to swing laterally of the car. The result of this construction has been that as the body of the car swung laterally, when rounding a curve or due to any unevenness in rail gauge or rail tilt, the detector coils carried by the detector carriage had a tendency to zig-zag laterally across the top of the rail. This has affected the accuracy of testing, because, as explained in said Sperry application, the detector coils should move over the rail in a definitely positioned relationship with respect to the width of the rail.

It is the principal object of my invention, therefore, to provide means whereby a constant lateral relationship will be maintained between the center longitudinal axis of the top of the rail and the detector coils.

Further objects and advantages of this invention will become apparent in the following detailed description thereof.

In the accompanying drawing,

Fig. 1 is a side elevation of the flaw detector carriage suspended from a car body, and showing one form of my invention applied thereto.

Fig. 2 is an enlarged view of a portion of Fig. 1, partly sectioned on the line 2—2.

Fig. 3 is a vertical section through the car body showing a mounting for one end of the detector carriage.

Referring to Fig. 1, I have herein disclosed the well known type of carriage 10, employed on the Sperry rail flaw detector car. This carriage is lowered from the car body 11 by piston rods 15 projecting from cylinders 16

swing laterally, and engages rail R by means of a front flanged wheel 13, and a similar rear wheel 14. Any suitable mounting of carriage 10 for lateral movement may be provided, such as that shown in the co-pending application of Walter M. Perry and George L. Jones, Serial No. 436,822 for Automatic rail locator for brushes of fissure detector car. Such mounting may consist of suitable pivotal supports for the cylinders 16, such as pivots 17 in brackets 18 fixed to the car body 11. The said pivots 17 may, if desired, be carried by gimbal ring 19 within which the cylinders may be pivoted at 29. The carriage supports brushes 24, 25 for leading current into and out of the rail and establishing an electro-magnetic field surrounding the same. From the carriage there is suspended a pick-up or detecting unit 20 consisting of a sled 21 in which are supported opposed coils 22, 23, intended to cut the electro-magnetic field surrounding the rail, so that where a flaw is encountered, a differential E. M. F. will be induced as the coils pass successively thereover, and the flaw is thus detected.

Under the conditions set forth in the preceding paragraph, it will be seen that when the car body 11 swings laterally when rounding a curve or for any other obvious reason, carriage 10, frame 12 and wheels 13, 14 may also move laterally. Should this occur, detector unit 20 will also move laterally across the top of the rail. The result of this movement of the coils has often been to cut the magnetic lines of force surrounding the rails at a different rate of speed, thus inducing a differential E. M. F. and causing an indication similar to that when a flaw is encountered, whereas no flaw in fact exists.

To obviate this possibility of error, I provide a simple means whereby the detector carriage 10 with its supported detector unit are at all times maintained in fixed lateral relationship with the top of the rail. For

this purpose I provide means whereby the wheels 13 and 14 are constantly urged in such direction as to cause the flanges thereof to engage the rail. This means takes the form of a turning or displacement of the plane of each wheel around the vertical axis so as to toe the wheels outwardly, so that their normal tendency will be to travel outwardly until the flanges engage the rail.

10 The displacement of the plane of the wheel around the vertical axis may be achieved by attaching to frame 12 a guide wheel support or yoke 30 fastened to frame 12 by means of bolts 31, 32. Between the frame and the yoke 15 I place a wedge-shaped member 33 in such manner that the yoke is tilted to twist the plane of the wheel with respect to the vertical in such direction that when the car is traveling in the direction of arrow A the wheel will tend to run outwardly until its flange engages the rail R. This toeing out of wheels 13 and 14 therefore tends to keep the wheel flanges constantly in engagement with the rail and thus maintains a constant relative 20 position laterally between the detector coils carried by the carriage and the rail.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other 30 means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

45 1. In a flaw detector for rails, a carriage mounted for lateral movement with respect to the rail and adapted to be moved along the rail, said carriage supporting detector means, and means associated with said carriage tending to maintain the same in fixed relationship with respect to said rail.

50 2. In a flaw detector for rails, a carriage mounted for lateral movement with respect to the rail and adapted to be moved along the rail, said carriage supporting detector means, and means associated with said carriage tending to maintain the same in fixed relationship laterally with respect to said rail.

55 3. In a flaw detector for rails, a carriage mounted for lateral movement with respect to the rail and adapted to be moved along the rail, said carriage supporting detector means and having a wheel engaging the rail, and means tending to maintain said wheel in

fixed relation laterally with respect to said rail.

4. In a flaw detector for rails, a carriage mounted for lateral movement with respect to the rail and adapted to be moved along the rail, said carriage supporting detector means and having a flanged wheel engaging the rail, and means tending to maintain said flange constantly in engagement with said rail.

75 5. In a flaw detector for rails, a carriage mounted for lateral movement with respect to the rail and adapted to be moved along the rail, said carriage supporting detector means and having a flanged wheel engaging the rail, and means tending to bias said wheel outwardly to cause said flange to engage said rail.

80 6. In a flaw detector for rails, a carriage mounted for lateral movement with respect to the rail and adapted to be moved along the rail, said carriage supporting detector means and having a flanged wheel engaging the rail, and means whereby movements of said flange away from the rail are resisted.

85 7. In a flaw detector for rails, a carriage mounted for lateral movement with respect to the rail and adapted to be moved along the rail, said carriage supporting detector means and having a wheel engaging the rail, the plane of said wheel being so inclined as to tend to move said carriage in a predetermined direction with respect to the rail.

90 8. In a flaw detector for rails, a carriage mounted for lateral movement with respect to the rail and adapted to be moved along the rail, said carriage supporting detector means and having a flanged wheel engaging the rail, the plane of said wheel being so inclined as to tend to move said wheel outwardly to cause said flange to engage said rail.

95 9. In a flaw detector for rails, a carriage mounted for lateral movement with respect to the rail and adapted to be moved along the rail, said carriage supporting detector means and having a flanged wheel engaging the rail, a yoke in which said wheel is mounted, and means including a wedge between said yoke and carriage whereby the plane of said wheel is displayed around a vertical axis so as to tend to move said wheel to cause said flange to engage said rail.

100 10. In a flaw detector for rails, a carriage mounted for lateral movement with respect to the rail and adapted to be moved along the rail, said carriage supporting detector means and having a plurality of wheels engaging the rail, and means tending to maintain said wheels in fixed relation laterally with respect to said rail.

105 11. In a flaw detector for rails, a carriage mounted for lateral movement with respect to the rail and adapted to be moved along the rail, said carriage supporting detector means and having a plurality of flanged wheels en-

gaging the rail, and means tending to maintain said flanges constantly in engagement with said rail.

12. In a flaw detector for rails, a carriage mounted for lateral movement with respect to the rail and adapted to be moved along the rail, said carriage supporting detector means and having a plurality of flanged wheels engaging the rail, said wheels being obliquely positioned to tend to move said wheels to cause said flanges to engage said rail.

In testimony whereof I affix my signature.
GEORGE L. JONES.
